T. E. NIBLOCK

FUSE CHANGER

Original Filed Feb. 16, 1922

INVENTOR
T. E. Niblock,

BY *Thurman L. Keo.*
ATTORNEYS

UNITED STATES PATENT OFFICE.

THOMAS E. NIBLOCK, OF GREAT FALLS, MONTANA.

FUSE CHANGER.

Application filed February 16, 1922, Serial No. 537,105. Renewed August 20, 1924.

To all whom it may concern:

Be it known that I, THOMAS E. NIBLOCK, a citizen of the United States, and a resident of Great Falls, in the county of Cascade and State of Montana, have invented certain new and useful Improvements in Fuse Changers, of which the following is a specification.

This invention relates to a fuse changer and more particularly to a device adapted for handling fuses used in connection with high voltage electrical circuits. It often occurs that fuses used in connection with high voltage electrical circuits blow and need to be replaced without the circuit being cut off. This is especially true in connection with primary circuits of potential transformers used for supplying voltage to instruments. To withdraw a blown fuse and substitute a new fuse while the primary circuit is still charged, places the operator in a precarious position, in that the high voltage is capable of jumping a considerable distance to a ground and thus produces the possibility of current jumping to ground thru the operator.

With the above in view, it is the primary object of the present invention to provide a device whereby a high potential fuse may be positioned under the circumstances mentioned without danger to the operator.

It is also an object of the invention that the device be easy to manipulate.

It is also within the scope of the objects of the invention that the device be exceedingly strong, simple in construction and inexpensive to manufacture.

Other objects and objects relating to details of construction, combination and arrangement of parts, will hereinafter appear in the detailed description to follow.

The invention is illustrated by way of example in the accompanying drawings, in which:—

Figure 1 is a view in side elevation of the fuse changer and also illustrating the manner in which the same may be operated.

Figure 2 is a vertical longitudinal sectional view of the same.

Figure 3 is transverse sectional view taken substantially on the lines 3—3 of Figure 2.

Figure 4 is a partial vertical sectional view similar to that shown in Figure 2 and illustrating the jaws when in distended position.

Referring to the drawings more particu-

larly, "H" indicates generally a handle which is provided with a central bore 10 and made of insulating material such as wood or the like. The handle is cylindrical in shape and elongated, as shown in Figure 1, and its one end is telescoped by a cap "C," the cap "C" being preferably of insulating material and consisting in a head portion 11, and a tubular portion 12, which telescopes the associated end of the handle "H." The head 11, of the cap "C" is provided with a central threaded bore, adapted to receive the threaded end 13 of the plunger "P." The plunger "P" is adapted to slide within the bore 10, of the handle "H" and is of insulating material. Between the end of handle extending with the cap "C" and the head of cap is interposed a coil spring 14, which is adapted to normally urge the handle "H" forward with respect to the cap "C." The end of the handle "H" opposite to that associated with the cap "C" is enlarged as at 15 and the bore 10 is also enlarged at the same end of the handle as at 16. This end of the handle has fitted thereon a ferrule "F" which consists in the cylindrical portion 17, which extends about the outer periphery of the enlarged portion 15 of the handle "H" and made flush therewith. The forward end of the cylindrical portion 17 continues into an inwardly extending portion 18 which is frusto-conical in shape and adapted to fit within the enlargement 16 of the handle bore 10. Within the frusto-conical portion 18 of the ferrule there is provided a wedge-shaped opening, and, within said opening there is fitted a pair of supporting members 19. The faces of the members 19 are adapted to fit one against the other when said members are positioned within the ferrule "F," as illustrated in Figure 2, while the outer edge of each member is adapted to fit within the tapered aperture 18 of the ferrule. Adjacent to the outer end of each member 19, and upon the outer edge thereof, there is provided an offset, and from said offset there extends a threaded stud 20. The studs 20 turnably support the pair of jaws "J." Each jaw "J" consists in a supporting portion 22 through which there is provided an opening adapted for receiving the associated stud 20. A wing nut 23 is provided for each stud whereby the jaws "J" may be adjustably held relating to their turning movement upon the studs, 20. The outer end por-

tion 24 of each jaw is arcuate in shape and recessed complemental to each other. Each jaw portion 24 has its free end formed with an arcuate shaped recess as at 25. When the 5 jaws 24 are brought together, as illustrated in Figure 2, the recesses 25 will enable the operator to grasp a small fuse between the end of the jaws, while between the inner edges of the jaws 24, a larger fuse may be 10 grasped, thus providing a means for grasping fuses of different diameter.

Each jaw supporting member 19 is connected to the plunger "P" by a metallic strip 26, said strip in each instance being resilient 15 and capable of spreading the supporting elements 19 apart, as illustrated in Figure 4, when positioned within the outer end of the ferrule. The members 26 are brought together at their inner ends as at 27 and properly secured to the plunger "P." The outer ends of each member 26 may be secured in 20 any suitable manner to the jaw supporting member 19.

In the use of the present device, assuming 25 that it is desired to change a primary fuse of a potential transformer on a high voltage circuit without cutting off the current, then the handle "H" should be grasped with one hand, as in Figure 1, and the cap "C" pressed forwardly on the handle "H" in order to force the plunger "P" forwardly to the position shown in Figure 4. In this position the jaw supporting elements 19 will be extended from the ferrule "F" and the 30 jaws "J" carried thereby will be brought to a position so that the fuse will be grasped between the concaved free ends thereof when said jaws are brought together. In case the fuse is of large diameter then the same 35 should be positioned so that it will be received between the inner concaved edges of the jaws "J." The handle "H" may now be permitted to return to its normal position with reference to the jaws "J," under the 40 tension of the spring 19, and thus grasp the fuse between the jaws "J." The fuse may now be pulled and a new one placed in between the jaws and positioned to replace the fuse which has been drawn or pulled.

50 It is pointed out that in placing a fuse in position, the fuse should be first positioned so that the ends are resting upon the spring clips to receive them and then a quick thrust upon the handle "H" will cause the fuse 55 ends to properly seat. Where the fuse to be manipulated is situated above the head of the operator, which is standard practice, it would be to an advantage to dispose the jaws at an angle to the longitudinal axis of the handle "H," as illustrated in dotted lines in 60 Figure 1. As is obvious by this arrangement, the fuses could be drawn horizontally,

and without any great effort on the part of the operator.

It is pointed out that the construction of 65 this device is such that the operator is entirely insulated from the fuse which is being drawn and thus any danger to the operator is eliminated.

While I have shown and described the preferred form of my invention, I wish it to be understood that the construction, combination and arrangement of parts, may be changed by those skilled in the art without departing from the spirit of the invention, 75 as indicated by the appended claims.

I claim:

1. A device of the character described, comprising a handle provided with a socket in its one end, a pair of distensible spring 80 fingers disposed in said socket and adapted to be drawn inwardly and within the handle for depressing the same toward each other, a supporting lug carried by each spring finger at its free end, and a jaw pivotally supported at the free end of each lug.

2. A device of the character described, comprising a handle provided with a socket in its one end, a pair of distensible spring fingers disposed in said socket and adapted to be drawn inwardly and within the handle for depressing the same toward each other, a supporting lug carried by each spring 95 finger at its free end, and a jaw pivotally supported at the free end of each lug and adapted for lateral swinging movement.

3. A device of the character described, comprising a handle provided with a socket at its one end, a bore extending longitudinally of the handle and communicating with 100 said socket, a pair of distensible spring fingers disposed within said socket, means for securing the inner ends of said spring fingers together for drawing the same within the bore of said handle whereby to depress said fingers toward each other, a rod extending through the longitudinal bore of said handle and connected to the inner ends of said spring fingers whereby the spring fingers may be drawn inwardly for depressing the free ends toward each other, a jaw carried 110 by each spring finger, a cap upon the other end of said handle with which the associated end of the lug is connected, and a spring interposed between said cap and the free end of said handle.

4. A fuse pulling device including a pair of opposing jaws, means whereby the jaws may be retracted or advanced with respect to each other, and an adjustable pivotal support for each jaw whereby to permit lateral swinging movement thereof.

THOMAS E. NIBLOCK,
